[57] CLAIM

The ornamental design for a scroller jig saw, as shown
and described.

DESCRIPTION

FIG. 1 is a front and right side perspective view of a
scroller jig saw showing my new design;

FIG. 2 is a right side perspective view thereof;

FIG. 3 is a left side perspective view thereof;

FIG. 4 is a front perspective view thereof;

FIG. 5 is a top perspective view thereof;

FIG. 6 is a bottom perspective view thereof; and

FIG. 7 is a rear perspective view thereof.

The power cord is shown broken-away in the views to
indicate indeterminate length.
